ATTORNEY.

UNITED STATES PATENT OFFICE.

HENRY W. KOCH, OF SAN FRANCISCO, CALIFORNIA.

BARREL-SEAL.

1,379,827.

Specification of Letters Patent.

Patented May 31, 1921.

Application filed March 31, 1920. Serial No. 370,084.

To all whom it may concern:

Be it known that I, HENRY W. KOCH, a citizen of the United States, residing at San Francisco, in the county of San Francisco, 5 State of California, have invented a new and useful Barrel-Seal, of which the following is a specification in such full and clear terms as will enable those skilled in the art to construct and use the same.

10 This invention relates to a barrel seal intended for preventing the wilful removal without authority of the contents of barrels, and its object is to provide means whereby a faucet may be securely locked, in addition 15 to providing means to cover the bung of the barrel and thereby prevent it from being tampered with.

It will be understood by those skilled in the art that barrels for the storage of liquors 20 frequently have faucets applied thereto, which are necessary to lock and that ordinarily means separate from the barrel must be applied to the faucet to prevent its being unlawfully opened.

25 In the present instance the means for locking the faucet is also provided with means to prevent it from being moved to one side of the bung, so that the bung may be securely protected as well.

30 Another object of the invention is to provide a lock for covering the barrel air vent in addition to the bung.

Other objects of the invention will appear as the description proceeds.

35 An embodiment of the invention is shown in the accompanying drawings in which the same reference numeral is applied to the same portion throughout, but I am aware that there may be modifications thereof.

40 Figure 1 shows the device applied to a barrel.

Fig. 2 is a vertical sectional view of the locking device adjacent the faucet.

45 Fig. 3 is a sectional view on the line 3—3, Fig. 2.

Fig. 4 is a perspective view of the points for preventing the strap from being moved laterally when it is secured in position.

50 Fig. 5 is a view of the bar used to prevent the locking straps from being moved laterally off the faucet and to prevent the locking thumb screw from being rotated.

55 Fig. 6 is a perspective view of one of the hooks on the ends of the straps for securing them to the chime of the barrel.

The numeral 1 indicates the barrel which

is provided with a faucet 2 having the valve stem 3 and operating handle 4. The locking device consists of a short strap 5 through which the threaded portion of the faucet 60 extends into the barrel. This strap has a hook 6 and a horizontal portion 7 provided with an open slot to receive the valve stem 3. The upper strap 8 has two sharp points 9 and 10 at about its middle portion adjacent 65 the bung 11, and it is provided with a hook 12 at its upper end, which passes over the upper edge of the barrel chime.

At the lower end of the strap 8 there is a horizontally extending member 13 which is 70 provided with a raised portion 14 to cover the valve handle.

A bolt 15 with a thumb nut 16 is used to secure the two horizontal portions of the straps together in the position indicated in 75 Figs. 1 and 2.

The wing nut of the bolt is provided with openings to receive a finger 17 on a bar 18 and said bar has a hole 19 through which the hasp 20 of the pad-lock 21 can be passed, 80 the hasp also passing through one of the holes in the wing nut 16.

When the liquid is to be withdrawn from the barrel, the pad-lock is removed and the bolt 15 is loosened to permit the strap 8 to 85 be moved enough to allow the handle of the valve stem to be rotated.

When the straps are placed in position, the points 9 and 10 are driven into the barrel with a slight tap of the hammer to prevent 90 the strap 8 from being moved sidewise off the bung, and the strap covers the air hole 25 as well.

What I claim is as follows, but various modifications may be made in the construction shown in the drawings and above particularly described form, within the purview of my invention.

1. A lock for barrel faucets comprising a pair of metal straps, each having a hook 100 to pass over the ends of the barrel staves, an extension on one of said straps to embrace the faucet valve stem, an extension on the other strap to prevent the valve stem from being rotated, and means to lock 105 the two straps.

2. A lock for barrel faucets comprising a pair of straps having hooks to embrace the ends of the barrel staves, an extension on one of the straps to embrace the faucet 110 valve stem, an extension on the other strap to prevent the valve stem from being ro-

tated, a lock to secure the two straps together and means to prevent one of the straps from being moved laterally on this latter portion.

5. 3. A lock for barrel faucets comprising a pair of straps having hooks on their ends to pass over the ends of the barrel staves, an extension on one of the straps to embrace the faucet valve stem, an extension on the 10 other strap to embrace the valve stem handle to prevent the valve from being rotated, means to secure the two straps together, means to prevent the straps from being turned laterally and a lock for securing the 15 two straps together.

4. A lock for barrel faucets comprising

a pair of metal straps having hooks on their ends for embracing the ends of the barrel staves, an extension on one of the straps provided with an open slot to embrace the 20 valve stem, an extension on the other strap for preventing the valve stem from being turned, a bolt for securing the two straps together, a bar, a lock for securing the bar to one of the straps and means adjacent the 25 middle of one of the straps to prevent it from being moved sidewise when locked in place.

In testimony whereof I have hereunto set my hand this 24 day of March, A. D. 1920.

30

HENRY W. KOCH.
